(57) **CLAIM**

We claim the ornamental design for the floor-standing liquid disinfectant dispenser, as shown and described.

DESCRIPTION

FIG. 1 is a perspective view of the floor-standing liquid disinfectant dispenser of the present invention;

FIG. 2 is a front elevational view thereof;

FIG. 3 is a back elevational view thereof;

FIG. 4 is a left-side elevational view thereof, the right-side elevational view being a mirror image;

FIG. 5 is a top plan view thereof; and,

FIG. 6 is a bottom plan view thereof.
